UNITED STATES PATENT OFFICE.

WALTER R. HOPE, OF WILMINGTON, DELAWARE.

METHOD OF MAKING DRAWINGS OR PICTURES.

1,240,143.

Specification of Letters Patent. Patented Sept. 11, 1917.

Application filed March 25, 1916. Serial No. 86,654.

To all whom it may concern:

Be it known that I, WALTER R. HOPE, a citizen of the United States, residing at Wilmington, in the county of New Castle, 5 State of Delaware, have invented a new and useful Method of Making Drawings or Pictures, of which the following is a specification.

In the methods heretofore employed in 10 making drawings which are to be reproduced, such as for example, shop drawings, it is customary to first make a lead pencil drawing either on detail paper or on tracing paper, after which the drawing is traced, 15 on linen with waterproof ink in order to make a permanent record. This renders it necessary to first make a drawing in pencil, then the drawing is checked, then traced, and the tracing is checked.

20 In accordance with my present invention, I eliminate several of these operations.

With the above in view, my invention, in 25 its broad and generic scope, consists in delineating the subject-matter to be illustrated with a copying pencil upon the material, and I then treat the delineations in such a manner as to render them permanent and form a permanent record, from which prints can be made by any desired or conventional 30 solar or other process.

It further consists of a novel method wherein the subject-matter is delineated upon a sheet of material with a copying pencil, and thereafter the delineation is subjected to vapor or to heat and vapor in order 35 to permanentize the delineation.

In the accompanying drawing which represents a plan view of a sheet of material with the delineations thereon, I have 40 illustrated the first step of carrying out my method.

Referring to this drawing, 1 designates a sheet of suitable material on which the delineation 2 is made.

45 In carrying out my invention, I take a sheet of material, the transparency of which is not affected by heat and moisture, and I preferably employ tracing paper or tracing linen. It will be understood that ordinary 50 tracing paper may be employed, but that when tracing linen or tracing cloth is employed, the same must be waterproof or impervious to moisture or of material which will not dissolve with moisture and make 55 the transparency defective. I then draw upon the sheet with a pencil, preferably em-

ploying an indelible or copying pencil. The pencil lines can be erased without smearing in case it is desired to correct them. After the drawing is corrected, I 60 subject it to a vapor bath or to vapor and heat, and one way of accomplishing this is by placing the material into a suitable receptacle into which the hot vapor is passed, although it is not necessary to employ a receptacle, as its only object is to keep the room in which the work is being done from being filled with vapor. This treatment sets the copying pencil marks on the linen or paper and also renders them 65 more distinct and legible. The delineation is permanentized and is of the same character as if it had been made of waterproof ink, and can be used for reproduction in 70 the same manner that a tracing made from 75 india ink is used.

I preferably employ a specially prepared tracing cloth or tracing paper, the transparency of which is not affected by heat or moisture. It has been found in practice 80 that in accordance with my present method, the delineation is permanentized and there is no possibility of any smearing or blurring, so that a permanent record is obtained.

The pencil that I employ in the practice 85 of my invention is the ordinary copying pencil, readily obtainable at all times on the market.

The practical advantage of my method will be fully appreciated when it is stated 90 that in order to set and keep a line made by a copying pencil from smearing, it is necessary to treat it with moisture; and it is equally necessary to attain this end without any object contacting with the line until 95 the same is completely set. From this it follows that the subjecting of the material bearing the fresh delineation to a vapor bath constitutes the salient feature of my invention.

100 It will now be apparent that I have devised a new and useful method of making drawings or pictures which embodies the features of advantage enumerated as desirable in the statement of the invention and the above description, and while I have, in the present instance, shown and described a preferred embodiment thereof which will give in practice satisfactory and reliable 105 results, it is to be understood that the same 110 is susceptible of modification in various particulars without departing from the

spirit or scope of the invention or sacrificing any of its advantages.

Having thus described my invention, what I claim as new and desire to secure by Letters Patent, is:-

The herein described method of making drawings or pictures, which consists in delineating the subject matter upon a sheet of material through the medium of a copy-

ing pencil, preventing contact of any object 10 with the subject matter so delineated, and then subjecting the material while the delineation is fresh to the action of vapor.

WALTER R. HOPE.
